UNITED STATES PATENT OFFICE.

JOHN HARRIS, OF CLEVELAND, OHIO.

CARBID-FEEDING MECHANISM FOR ACETYLENE-GENERATORS.

1,234,161.

Specification of Letters Patent. Patented July 24, 1917.

Original application filed October 12, 1914, Serial No. 866,194. Divided and this application filed March 22, 1915. Serial No. 16,150.

To all whom it may concern:

Be it known that I, JOHN HARRIS, a citizen of the United States, residing at Cleveland, in the county of Cuyahoga and State 5 of Ohio, have invented a certain new and useful Improvement in Carbid-Feeding Mechanism for Acetylene-Generators, of which the following is a full, clear, and exact description, reference being had to the 10 accompanying drawings.

This invention relates to acetylene-gas generators of the type shown in my co-pending application, Serial No. 866,194, filed October 12th, 1914, and of which this application is a division; the generators being 15 employed for producing acetylene-gas of high pressure, such as is used with blow-pipes for so-called "autogenous welding."

My present invention relates particularly 20 to carbid feeding mechanism for use with apparatus of the above character; and it has for its object the provision of mechanism that is comparatively simple of construction and positive of action, for automatically 25 feeding or transmitting the carbid from the carbid hopper to the generating chamber of the apparatus.

Generally speaking my invention may be 30 defined as consisting of the combinations of elements set forth in the annexed claims and illustrated in the accompanying drawings forming part hereof, wherein Figure 1 is a front elevation of an apparatus embodying my invention; Fig. 2 is a central vertical 35 sectional view through the neck of the generator and a portion of the carbid hopper, and includes the carbid feeding mechanism, said view being taken on a plane parallel to the front elevation; Fig. 3 is a horizontal section 40 taken substantially on the line 3—3 of Fig. 2; Fig. 4 is a view, similar to Fig. 2, but taken on a plane at right angles to said figure, and shows the parts on a somewhat smaller scale; Fig. 5 is a central section 45 through the diaphragm and its casing, by means of which the carbid feeding mechanism is automatically controlled; and Fig. 6 is a detail, in perspective, of certain parts of the weight motor whereby the carbid feeding 50 mechanism is operated.

Taking up a detailed description of the invention by the use of reference characters, 1 represents the generating chamber of the apparatus, above which is supported, upon 55 a neck 2, and a carbid hopper 3.

The filling opening of the hopper is adapt-

ed to be closed by a cover 4 that is clamped to the opening by a screw 5, which is threaded through a yoke 6, the ends whereof are pivoted to the hopper on opposite sides of the 60 filling opening. This is in accordance with the usual method of closing receptacles of this kind, and forms no part of my invention.

Water may be supplied to the generating 65 chamber 1 through the open-top receptacle 7, that is communicatively connected to the chamber, through the pipe 8. A valve 9 is included in the pipe 8, and has an operating handle 10 which, it may be stated, is connected by a rod 11 with the gate of the sludge valve 12, in such a way that said sludge valve cannot be opened without first opening the valve 9. This feature constitutes no part of my present invention, but, 75 together with certain other safety appliances, is made the subject of my co-pending application Serial Number 866,194, filed Oct. 12, 1914. The filling receptacle 7 answers also as a water level indicator to show 80 when the generating chamber is full. An overflow pipe 13 has connection with the side of the receptacle 7 at an elevation which corresponds to the high-water level of the generating chamber. By opening the valve 85 9, and placing the end of a hose in the open top of the filling receptacle, water may be supplied to the apparatus until it is seen to rise within the receptacle to the height of the 90 overflow pipe 13.

Shown generally at 20, in Fig. 1, is a weight motor that is supported upon a bracket 21 which extends from one side of the hopper 3. This weight motor may be of any approved type, and derives its power 95 from the weight 22 which is suspended from the end of a cable 23 that passes over a sheave 24, journaled in the outer end of the bracket 21, and which cable is finally attached to the drum 25. Through suitable gearing, this drum, as it is rotated through the influence of the weight 22, drives the beveled pinion 26 that meshes with a similar pinion 27, fastened to the upper end of shaft 28, which shaft may be provided with the 100 universal joints 29, said joints being included for the obvious reason of allowing a slight difference in the alinement in the ends of the shaft 28.

A crank case 30 extends from one side of 110 the neck 2 of the apparatus, and in a vertical extension 31 which rises from the upper sur-

face thereof, is journaled the lower end of the aforesaid shaft 28, a suitable packing gland 32 being employed to form a gas-tight joint where said shaft enters the extension. Within the crank casing, the shaft is provided with a crank 33, to which is pivoted one end of a connecting rod or link 34, the opposite end of which is pivoted, at 35, to a rod 36, which passes directly through the neck of the generator and has its opposite end slidably supported within a bushing 37 that is retained within a gas-tight tubular extension 38, that projects from the side of the neck. From the preceding description it will be seen that, as the shaft 28 is rotated by the weight motor, the rod 36 will be reciprocated.

Fastened to the rod 36 at about the center of the neck, is a scraper 40 which slides upon a circular shelf 41, supported from the sides of the neck by angle brackets 42. (See Fig. 4.) Two diametrically opposite side extensions of the shelf 41 are shown as turned upward to provide brackets 43 within the upper ends of which are journaled the ends of the arms 44 of the semicircular shells 45, the lower edges of which rest upon the periphery of the shelf 41. Each of the shells is divided into two parts, the adjacent ends of which are held together by the U-shaped members 46, said adjacent ends of the two parts being separated sufficiently to allow the rod 36 to play freely within the space between said ends. An agitator 47 is pivoted, at 48, to the scraper 40 and acts to keep the mass of carbid from becoming too closely packed within the contracted lower end of the hopper, said agitator being capable of a slight oscillation about its pivot, the maximum limits of this oscillation being defined by the sides of the mouth of the hopper.

Included within the mechanism of the weight motor, is a brake drum 50, with which is adapted to coöperate either end 51 or 52 of an angle lever 53, suitable friction shoes being employed between the respective ends of the lever and the drum. The lever 53 is fastened to a rock shaft 54 which projects through the side of the casing and has attached to its end, an arm 55. The free end of the arm 55 connects with the upper end of a rod 56, and the opposite end of this rod is pivoted to the forward end of an arm 57 which is pinned to a shaft 58 that is journaled within the upper half 59 of a diaphragm casing that is located above, and carried by the crank case 30. The lower half 60 of this diaphragm casing has communication with the interior of the apparatus through the nipple 61—it being understood that the interior of the crank case opens into the generating chamber—and clamped between the adjacent edges of the two parts of the casing is a flexible

diaphragm 62 (see Fig. 5). A pin, having an enlargement 64, is clamped to the central portion of the diaphragm, by the nut 65, suitable plates being applied to each side of the diaphragm. Resting upon the upper end of the enlargement 64, is the bifurcated end of an arm 66 that is pinned to the shaft 58 where it projects within the diaphragm casing. A compression spring 67 tends to force the free end of the arm 66 downward, said spring having its opposite end bearing upon the end of a cap 68 that is threaded into the upper end of the casing member 59. A finishing cap 69 incloses the spring cap 68.

The operation of the carbid feeding mechanism is as follows: It will be assumed that a quantity of carbid has fallen from the hopper and is resting upon the shelf 41, and that all parts of the apparatus are in proper condition for the generation of gas. The weight motor will operate to rotate the shaft 28, and through the crank 33 and the connecting link 34, to reciprocate the rod 36 and scraper 40. Upon the movement of the scraper in one direction, the body of carbid which is on the advancing side thereof will be shoved over against the adjacent shell 45 and swing the same away from the edge of the shelf, thereby allowing a part of the carbid to tumble over the edge of the shelf into the water contained within the generating chamber below. As the scraper moves in the opposite direction, the carbid on the other side thereof will be acted upon in the same manner as that which has just been precipitated into the water, and the former shell 45 will return to normal position. As gas is generated and accumulates in the apparatus, it will act upon the underneath side of the diaphragm 62 and elevate the same, thereby lifting the free end of the arm 66 and rocking the shaft 58. Through the arm 57 that is attached to the outer end of said shaft, the rod 56 will be pushed upward to rock the arm 55, shaft 54 and the angle lever 53 in a direction to cause the end 52 thereof to be brought into contact with the brake drum 50. The operation of the weight motor will thus be suspended until sufficient gas has been withdrawn from the apparatus to lower the pressure therein enough to allow the aforesaid parts to assume normal position and free the brake of the motor.

In case the diaphragm 62 becomes fractured, the gas which would thus be permitted to escape into the upper portion 59 of its casing, would be led off through a vent pipe 70, which joins said casing, as shown in Fig. 5.

Having thus described my invention, what I claim is:

1. Carbid feeding mechanism comprising, in combination, a support for a quantity of

carbid and having opposed edges from which the carbid may be discharged, members for coöperation with said edges and movable independently of each other toward and away from the same, a device that is movable across the support to push the carbid toward the aforesaid members, and means for moving said device.

5. Carbid feeding mechanism comprising, in combination, a shelf for supporting a quantity of carbid and from the opposed edges of which the carbid is discharged, shells for coöperation with said edges of the shelf and movable independently of each other toward and away from the same, a scraper that is movable transversely of the shelf and in the direction of the shells, and means for moving said scraper.

10. Carbid feeding mechanism comprising, in combination, a support for a quantity of carbid and having an edge from which the carbid may be discharged, a shell normally reposing with its edge coincident with the aforesaid edge of the support, said shell having opposed vertical extensions, supporting means to which the upper ends of said extensions are pivoted so that the shell is swingable toward and from the aforesaid edge of the support, a device that is movable across the support to push the carbid toward the aforesaid shell, and means for moving said device.

15. Carbid feeding mechanism comprising, in combination, a support for a quantity of carbid and having an edge from which the carbid may be discharged, a shell normally reposing with its edge coincident with the aforesaid edge of the support and having a vertical extension that is rigid with its body portion, supporting means to which the upper end of the extension is pivoted, whereby the shell is swingable upward and away from the aforesaid edge of the carbid support, a device that is movable across the support to push the carbid toward the shell, a push rod having connection with said device and extending across the discharge edge of the support, the aforesaid shell having a slotted extension that

50. prevented from moving transversely of the rod, guides through which the rod is movable in a fixed path, and means for moving said rod.

5. Carbid feeding mechanism comprising, 55 in combination, a shelf for supporting a quantity of carbid and from the opposed edges of which the carbid is discharged, a shell having an edge coincident with the aforesaid opposed edges of the shelf, each 60 shell having opposed vertical extensions which terminate some distance above the transverse center of the shelf, supports wherein the upper ends of said extensions are pivoted, a device that is movable across 65 the shelf to push the carbid toward said shells, a rod to which said device is attached, said rod extending across the shelf transverse its aforesaid opposed edges, guides through which said rod is movable in a fixed path, 70 each shell having a slotted extension for guidance upon the rod, and means for reciprocating the rod.

6. In apparatus of the character set forth, the combination of a carbid hopper having a 75 downwardly convergent discharge end, a shelf supported below the discharge end of the hopper, a device movable across said shelf for pushing the carbid therefrom, means for moving said device, and an agitating member connected to said device and projecting upward into the discharge end of the hopper.

7. In apparatus of the character set forth, the combination of a carbid hopper having 85 a downwardly convergent discharge end, a shelf supported below the discharge end of the hopper, a device movable across said shelf for pushing the carbid therefrom, means for moving said device, and an agitating member pivotally connected to said device and projecting upward into the discharge end of the hopper.

In testimony whereof, I hereunto affix my signature in the presence of two witnesses.

JOHN HARRIS.
